MATERIAL HANDLING APPARATUS

Joseph F. Reedy, Greensburg, Pa.

Application May 17, 1950, Serial No. 162,513

1 Claim. (Cl. 212—81)

1

This invention relates to material handling apparatus and more particularly to the control of the holding and closing cables of apparatus employing a conventional clamshell bucket.

The primary object of the invention is to positively hold a clamshell bucket in open or closed position during the movements thereof so as to avoid spilling of the contents while it is being moved from a loading to a discharging position.

Another object is to assure the maintenance of the bucket in open position as it approaches the material to be handled thereby.

Still another object is to avoid overloading the closing line engine and to distribute the load uniformly between the holding line and closing line engine during the elevation and transportation of a loaded bucket.

The above and other objects may be attained by employing this invention which embodies among its features selectively engageable means connected to the engines for causing the cables to move at the same lineal speed during the movement of a conventional clamshell bucket.

Other features include remote control means mounted in the control cab within easy reach of the operator's station for governing the selectively engageable means whereby the movements and opening and closing of the clamshell bucket of the apparatus may be easily controlled by the operator.

Still further features include a gear train coupled to the holding line and closing line engines of a conventional loading and unloading apparatus employing a clamshell bucket, and clutch means connected to the gear train by which driving connection between the two engines may be established.

In the drawings:

Figure 1 is a schematic view of a conventional material handling apparatus of the type employing a clamshell bucket and showing one embodiment of this invention connected to the holding and closing engines.

Figure 2 is a top plan view of the holding and closing engines of a conventional material handling apparatus showing one embodiment of this invention coupled thereto for operation in connection therewith.

Figure 3 is an enlarged view of a conventional clamshell bucket showing in dotted lines the relative position of the parts when the bucket is open and closed.

Figure 4 is a wiring diagram showing the one embodiment of remote control for the clutch.

2

Referring to the drawings in detail a conventional material handling tower designated generally 10 is equipped with a boom 12 on which a conventional trolley 14 is mounted to move longitudinally in a horizontal rectilinear path. Carried by the tower 10 is a conventional platform 16 on which a conventional closing engine 18, and a conventional holding engine 20 is supported. The closing engine 18 comprises a conventional electrical motor 22 to the drive shaft 24 of which is connected a pinion 26 which meshes with a drive gear 28 of a cable drum 30; and also carried by the drive shaft 24 of the engine 18 is a conventional spring set brake 32 which is electrically released when power is supplied to the motor 22 in a conventional manner.

The holding engine 20 employs a conventional electric motor 34 to the drive shaft 36 of which is connected a drive pinion 38 having meshing engagement with a drive gear 40 which drives a drum 42 on which the holding cable of the apparatus is wound in a conventional manner. Like the engine 18, the engine 20 is equipped with a conventional electrically released spring set brake 44 which releases automatically when the motor 34 is energized. The structure thus far is of conventional form and well known in the art.

Carried by the trolley 14 are pairs 46 and 48 of sheaves over which the holding cable 50 and the closing cable 52 leading from their respective drums 42 and 30 are trained. The holding cable passing through one of each pair of sheaves 46 and 48 extends downwardly and is trained over a sheave 54 carried on the upper side of a crosshead 56 which is connected through the medium of links 58 and 60 to the opposite jaws 62 and 64 of a conventional clamshell bucket designated generally 66. These jaws 62 and 64 are pivotally coupled together by a transversely extending bar 68 upon which a sheave 70 is mounted to rotate. Carried by the crosshead 56 on the under side thereof is a sheave 72 and the closing cable 52 extends beneath the sheave 68 and thence upwardly around the sheave 72 and again downwardly around the sheave 68 and thence upwardly to the second pair of sheaves in the pairs 46 and 48. This closing cable is connected to the drum 30 of the closing engine 18 and has one end anchored to the tower 10 in any conventional manner. It will thus be seen that when the weight of the bucket 66 is supported on the holding cable 52 downward pull will be exerted on the crosshead 56 to cause the jaws 62 and 64 to move to closed position, and when the weight of the bucket is sustained

50 55

on the cable 50 around the sheave 54, the weight will be transferred to the crosshead 56 thus causing it to move upwardly and move the jaws 62 and 64 to open position. The construction of the clamshell bucket just described and its operation are all conventional and well known in the art, and it is evident that with this type of device extremely delicate control of the holding and closing cables 50 and 52 respectively must be maintained in order to assure correct operation of the device. Hence the successful manipulation of clamshell buckets of the type referred to requires the exercise of great skill by the operator.

In order to assure positive control of the opening and closing of the buckets, and to distribute the load uniformly between the closing and holding engines 18 and 20 respectively I employ a gear train designated generally 74 which comprises a gear 76 which is keyed or otherwise fixed to the shaft 24 to rotate therewith, and meshing with this gear 76 is a idler pinion 78. A gear 80 meshes with the idler pinion 78 and is mounted on a sleeve 82 which rotates about a shaft 84. A clutch member 86 is carried by the sleeve 82 and has driving connection therewith, and fixed to the shaft 84 is a cooperating clutch member 88, the engagement of which with the clutch member 86 is controlled by a cone or disks 90 which is mounted on the shaft 84 to slide longitudinally thereof. A gear 92 is fixed to the shaft 84 in spaced relation to the gear 80 and meshes with an idler pinion 94 which in turn meshes with a gear 96 which is fixed to the shaft 36. It will thus be seen that when the clutch members 86 and 88 are engaged, the drums 30 and 42 of the engines 18 and 20 respectively will be driven in unison. It is obvious that if the drums 30 and 42 are of the same diameter, and are driven at the same rate of speed, the lineal speed of the cables 50 and 52 will be the same. On the other hand should there be a variation between the diameters of the drums 30 and 42, the gears in the gear train 74 may be altered so that the larger of the drums may be driven at a lower rate of speed so that the cables 50 and 52 may be moved at the same lineal speed when the clutch members 86 and 88 are engaged.

In order to control the engagement and disengagement of the clutch members 86 I provide yielding means 98 which normally holds the clutch members in disengaged relation, and pivotally connected to the cone 90 is a yoke 100 having a laterally extending arm 102. This yoke is pivotally mounted at 104 at the junction of the arm 102 therewith so that when the arm is moved vertically, the yoke will be moved against the effort of the spring 98 to engage the clutch member 88 with the clutch member 86 and thereby establish driving connection between the gear 80 and the shaft 84. Any suitable type of servomotor 106, such as a solenoid is mounted adjacent the lever 102, and the core 108 of said solenoid is coupled as at 110 to the lever 102 so that when the solenoid is energized, the lever 102 will be moved in a direction to advance the cone 90 and engage the clutch members 88 and 86. A lead 112 coupled to one terminal of the solenoid is carried to one terminal of a suitable power source 114, the opposite terminal of which is connected through the medium of a conductor 116 to one terminal 118 of a push button which is located at a convenient place in the cab 120 occupied by the operator of the material handling equipment. The opposite lead 122 which is connected to one terminal of the sole-

noid is carried to the opposite contact 124 of the push button so that upon operating the push button, a flow of energy will be established through the solenoid to cause the clutch member 88 to engage the clutch member 86 and thereby establish driving connection between the holding engine and the closing engine. Obviously so long as the contacts of the push button are engaged, the holding and closing engines will operate in unison so as to cause the holding and closing cables 50 and 52 respectively to move at the same lineal speed. By thus moving the cables it will be evident that relative movement between the sheaves 54, 70 and 72 cannot take place and hence the bucket 66 will be held in the desired position irrespective of the speed at which the cables are driven. While an electrical clutch control system has been described, it is obvious that any suitable remote control system may be employed, so long as the clutch member 88 may be engaged with the clutch member 86 against the effort of the spring 98.

In operation the clutch members 86 and 88 are disengaged so that the cables 50 and 52 are independently regulated according to the desire and skill of the operator. Having manipulated the cables to cause the bucket to open, it is evident that by engaging the clutch members 86 and 88, the bucket may be lowered at full speed to engage the material to be loaded. When the bucket contacts the material to be loaded, the operator may disengage the clutch members, and by manipulating the controls of the closing engine to lift the bucket to exert lifting power on the cable 52 it will be evident that the jaws 62 and 64 of the bucket 66 may be closed about the load. With the closing of the jaws, the clutch members 86 and 88 are engaged so that both the holding and closing cables may exert lifting power on the bucket, and the load will be uniformly distributed between the motors 22 and 34, thus avoiding the overloading of either of the motors. Also since the cables move at the same lineal speed, it is evident that the relative positions of the sheaves 54 and 70 cannot change during the movement of the bucket. When it is desired to unload the bucket, it is only necessary to disengage the clutch members 86 and 88 and to transfer the load of the bucket to the holding cable and by paying out a small amount of the closing cable from the drum 30, it is evident that the bucket jaws 62 and 64 will move to open position and permit the contents to fall out of the bucket. In this way the opening, closing and the maintenance of the bucket in closed or open position irrespective of the speed at which it may be raised or lowered is under direct positive control of the operator at all times.

While in the foregoing there has been shown and described the preferred form of this invention, it is to be understood that minor changes in the details of construction, combination and arrangement of parts may be resorted to without departing from the spirit and scope of the invention as claimed.

I claim:

In a material handling apparatus, the combination of a boom and cable supported clamshell bucket and an operating means for the jaw controlling cables thereof, said means comprising a pair of drums spacedly mounted at one end of the boom, one for each of the said controlling cables, an electric motor for driving each of the drums, a gear train operatively connect-

ing each motor to its respective drum, another gear train interposed between the first gear trains, a clutch mechanism for connecting and disconnecting the said another gear train to and from the first gear trains, a brake on the shaft of each motor adapted to be automatically released when its respective motor is energized, and means for controlling the operation of the clutch mechanism, said motors operating to drive both drums simultaneously when energized and the clutch mechanism is set to connect said other gear train with the first gear trains and to drive said drums separately when the clutch mechanism is inoperative.
